Primary Examiner — Daniel J Domino

Assistant Examiner — Samina Vieth

(74) Attorney, Agent, or Firm — Zagorin Cave LLP;
 Robert W. Holland(57) **CLAIM**

We claim the ornamental design for a storage drive enclosure, as shown and described.

DESCRIPTION

FIG. 1 is a front perspective view of the storage drive enclosure comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and,

FIG. 9 a rear perspective view thereof.

Broken lines shown in the drawings illustrate portions of the storage drive enclosure and form no part of the claimed design.

1 Claim, 7 Drawing Sheets(56)
